ATTORNEY.

UNITED STATES PATENT OFFICE.

GUSTAVE HAACK, OF MADISON, WISCONSIN.

OUTBOARD BUOY FOR BOATS.

1,417,824.

Specification of Letters Patent. Patented May 30, 1922.

Application filed January 3, 1922. Serial No. 526,803.

To all whom it may concern:

Be it known that I, GUSTAVE HAACK, a citizen of the United States, residing at Madison, in the county of Dane and State 5 of Wisconsin, have invented certain new and useful Improvements in Outboard Buoys for Boats, of which the following is a specification.

My invention relates to outboard buoys 10 for boats; and the objects of my invention are, first, to provide an outboard tubular air chamber to be attached to both sides of a boat, between the water-line and gunnel; second, to provide brackets to be attached 15 to the stem and sides of the boat with a plurality of holes for locating the tubes at different distances from the gunnel; third, to provide closures for the ends of the tubes with projecting plates adapted to be secured 20 to the brackets by screws or bolts; and fourth, to have metal nipples and check valves disposed in the front closures for admitting and retaining compressed air in the tubes.

25 I attain these objects by the mechanism shown in the accompanying drawing in which—

- Fig. 1, is a plan;
- Fig. 2, is a side elevation;
- 30 Fig. 3, is an end elevation of the aft closure;
- Fig. 4, is a side elevation of same attached to tube;
- Fig. 5, is a rear elevation of after bracket;
- 35 Fig. 6, is a front elevation of same;
- Fig. 8, is a plan of the stem bracket;
- Fig. 7, is a side elevation of same.
- Similar numerals refer to similar parts throughout the several views.
- 40 The air tubes 1, are preferably of alu-

minum with an end closure 2, soldered to the rear end of same, said closure being provided with an outwardly extending plate 3, adapted to be fastened to a bracket 4, on the outside of a boat by screws 5. A somewhat 45 similar closure 6, is soldered to the front ends of the tubes, with a valve 7, for admitting and retaining compressed air, a plate 8, extends forward from the closure adapted to be secured to a bracket 9, by a bolt 10, 50 said bracket 9, to be securely fastened to the stem of the boat by screws or rivets 11.

The tubes 1, as described will add buoyancy to a boat in a rough sea and prevent the bow being submerged, and also prevent 55 dangerous rolling and capsizing as the rolling is arrested by the tubes before the water reaches the gunnel.

Having thus described my invention, I claim.

In a device of the kind described, closed 60 metal tubes containing compressed air and extending along both sides of a boat between the water-line and gunnel, said tubes provided with plates extending outward from 65 the ends thereof, a bracket with a plurality of holes secured to the stem of the boat and the forward plates fastened to the bracket by a bolt, brackets secured to both sides of the boat, a plurality of holes through said 70 brackets in which screws are disposed for attaching the plates at the rear ends of the tubes thereto, and means for admitting and retaining compressed air in the tubes.

In testimony whereof I affix my signature 75 in the presence of two subscribing witnesses,

GUSTAVE HAACK.
